US00D794081S

(12) **United States Design Patent** (10) **Patent No.:** **US D794,081 S**
(45) **Date of Patent:** **** Aug. 8, 2017**

(54) **MOTORCYCLE IGNITION COIL HEAT SINK**

(71) Applicant: **Accel Performance Group LLC**,
Bowling Green, KY (US)

(72) Inventors: **Jason Ellison**, Elyria, OH (US);
Michael T. Gretchko, Avon, OH (US)

(73) Assignee: **Accel Performance Group LLC**,
Bowling Green, KY (US)

(**) Term: **15 Years**

(21) Appl. No.: **29/562,295**

(22) Filed: **Apr. 25, 2016**

Related U.S. Application Data

(62) Division of application No. 29/493,752, filed on Jun. 12, 2014, now Pat. No. Des. 776,165.

(57) **CLAIM**

The ornamental design for a motorcycle ignition coil heat sink, as shown and described.

DESCRIPTION

FIG. 1 is a front perspective view of the motorcycle ignition coil heat sink;

FIG. 2 is a front elevation view thereof;

FIG. 3 is a left side elevation view thereof;

FIG. 4 is a rear elevation view thereof;

FIG. 5 is a right side elevation view thereof;

FIG. 6 is a top plan view thereof; and,

FIG. 7 is a bottom plan view thereof.

In the drawings, the broken lines depict environment and form no part of the claim.
